US0D1059065S

(12) **United States Design Patent** (10) **Patent No.:** **US D1,059,065 S**
(45) **Date of Patent:** **** Jan. 28, 2025**

(54) **CHAIR**

(71) Applicant: **VICCARBE HABITAT, S.L.**,
Beniparrell (ES)

(72) Inventor: **Stefan Diez**, Munich (DE)

(73) Assignee: **VICCARBE HABITAT, S.L.**,
Beniparrell (ES)

(**) Term: **15 Years**

(21) Appl. No.: **29/897,807**

(22) Filed: **Jul. 19, 2023**

(30) **Foreign Application Priority Data**

Jan. 19, 2023 (EM) 015009397-0001

(51) **LOC (15) Cl.** **06-01**

(52) **U.S. Cl.** **D6/380**
USPC .....

(58) **Field of Classification Search**
USPC D6/334-336, 373, 374, 375, 379, 380,
D6/381, 716, 716.1, 716.2, 716.4
CPC A47C 1/02; A47C 1/037; A47C 4/028;
A47C 7/14; A47C 7/24

See application file for complete search history.
